UNITED STATES PATENT OFFICE

149,399

DESIGN FOR A CHAIR

Herbert S. Beall, Norfolk, Va.

Application November 8, 1946, Serial No. 134,627

Term of patent 14 years

(Cl. D15—8)

To all whom it may concern:

Be it known that I, Herbert S. Beall, a citizen of the United States of America, residing at Norfolk, in the county of Norfolk and State of Virginia, have invented a new, original, and ornamental Design for a Chair, of which the following is a specification, reference being had to the accompanying drawing, forming part thereof.

The figure is a perspective view of a chair, showing my new design.

I claim:

The ornamental design for a chair, substantially as shown.

HERBERT S. BEALL.
